DRIVING MECHANISM FOR DYEING MACHINES

John E. Petersen, Irvington, N. J., assignor to
The Van Vlaanderen Machine Company, Pater-
son, N. J., a corporation of New Jersey

Application June 11, 1931, Serial No. 543,564

1 Claim. (Cl. 248—15)

In dyeing and the like machines of the class employing reels to advance the material being treated through the liquor the reel has one of its axial supports (as one end of an axial shaft of 5 the reel) journaled in a permanently located horizontal bearing but the other end is journaled in the bearing of a housing upstanding from a horizontal platform which is adjustable on a horizontal axis crossing that of the reel at right angles thereto so that it is possible to bring the second bearing into true axial alignment with the first, said housing containing gearing between the second axial support of the reel and the shaft of a motor carried by the platform. The fault 10 of this construction is that in time, if the alignment is initially true it is possible for the second bearing to assume more or less angular relation to the first as an incident not only of use of the machine but principally because the first bearing and said platform are carried by standards bolted 15 to the sides of the wooden liquor vat or tub of the machine and due to the warping of these sides the standards do not retain their original position; if, therefore, readjustment of said platform to re-align the bearings is neglected, or if it is not perfectly effected in the first instance, the reel binds in its bearings and does not run freely or uniformly, with consequent injury to the bearings and a waste of power to drive the reel. One 20 object of this invention is to avoid this fault. Another object is to provide for supporting the motor independently of the housing and at a lower elevation, where its weight will be less of a factor in disturbing the position of the standard 25 involved, and also so that it may be set in proper relation to the input element of the gearing notwithstanding some possible variations in size or discrepancies in the form of the motor base.

In the drawings,

40 Fig. 1 is a side elevation, partly in section, of so much of a dyeing machine as directly includes the present improvement; and

Fig. 2 is a section on substantially line 2—2, Fig. 1, showing the motor in side elevation.

45 Affixed to the wooden sides of the vat 1 are, as usual, the mentioned standards 3—4, a fragment only of standard 4 appearing in Fig. 1. 5 designates the reel and 6—6a its axial supports. The upper end of the standard 4 has, it will be understood without detailed illustration, a suitable bearing for the axial support 6a. The upper end of the standard 3 is formed with a housing 7 in which are spaced bearings 9 for a sleeve 10 which has its bore 10a tapered from both ends and receiving the axial support 6; this sleeve is kept

from longitudinal displacement in the bearings by flanges 10b, one of which may be screwed thereon as shown. The inner end of the sleeve is formed as a clutch, at 10c, and with this is adapted to engage a clutch member 11 splined on 60 the axial portion 6 and having connected therewith a lever 12 fulcrumed in the housing and protruding therefrom to afford a handle for operating it. On the sleeve, between the bearings, is fixed a worm-wheel 13, whereby, as will appear, the reel is driven. Thus, while the driving power is desirably applied to rotate the reel between the bearings 9 for the sleeve, the sleeve need not have its axis perfectly aligned with that of the reel but may assume, either initially or in 65 use of the machine, some more or less angular relation thereto without resulting in any binding or cramping or undue wear of the parts when the reel is being driven. Engaged with the worm-wheel is a worm 14 journaled in the housing vertically and having its lower end depending therefrom.

The motor is shown at 15, with its axis vertical. It is mounted, as will appear, on the side standard under the housing, which projects laterally somewhat. Since the weight of the motor is assumed by the standard at a lower elevation than heretofore and also inward thereof, as will appear it acts with less force to tend to tilt the standard.

Its shaft 16 projects upwardly and is coupled to 80 the depending end of the worm at 17. In order to bring the elements of the coupling together and obtain true alignment of the motor shaft and worm and also to impose the weight of the motor to best advantage on the standard 3 the motor 85 is connected with said standard as follows: The motor has a base consisting (here) of four feet 18. This base extends parallel with the motor shaft. The standard forms a fixed support and on this is supported, flanking the same, an up-right intermediary support for the motor consisting here of a pair of plates 19 provided with vertical slots 20 receiving screws 21 screwed into the motor base and by which the motor is clamped to this intermediary support. The intermediary 90 support is shiftable on the fixed support in a path toward and from the same and also horizontally and crosswise of said path. To this end one of the supports (here the intermediary support) includes horizontal studs 22 received in 105 horizontal slots 23 in spaced cross-bars 24 of the fixed support and provided with clamping nuts 25. The motor extends through the opening between the cross-bars. The adjustments thus possible—the motor on the intermediary support and 110

such support on the fixed support, as described—
make it possible to bring the elements of the
coupling 17 into proper relation to each other. To
reinforce the studs 22 against the weight of the
5 motor set-screws 26 tapped into the standard and
bearing upwardly against the plates may be em-
ployed.

Having thus fully described my invention what
I claim is:

10 The combination of a fixed upright support
having an opening therethrough from one to the
opposite upright side thereof, an intermediary
support arranged at one side of the fixed sup-
port and bridging the opening, horizontal studs
15 on the fixed support carrying the intermediary

support and adjustable lengthwise of themselves
through one of the supports and also slideable
transversely of themselves in one of the supports,
a motor arranged at the side of the fixed sup-
port opposite that at which the intermediary sup-
port is arranged and projecting through the open-
ing and adjustable on the intermediary support
transversely of the paths in which said studs are
adjustable transversely of themselves, and means
to secure said fixed support, the studs, the inter-
mediary support and motor in fixed relation to
each other upon adjustment of the studs and mo-
tor.

JOHN E. PETERSON.
